UNITED STATES PATENT OFFICE.

GEORGE C. PYLE, OF WILMINGTON, DELAWARE, ASSIGNOR TO DANIEL H. KENT, OF SAME PLACE.

MACHINE FOR PUNCHING HORSESHOES.

SPECIFICATION forming part of Letters Patent No. 284,201, dated November 9, 1880.

Application filed October 2, 1879.

To all whom it may concern:

Be it known that I, GEORGE C. PYLE, of the city of Wilmington, county of New Castle, and State of Delaware, have invented certain 5 new and useful Improvements in Machines for Punching Horseshoes, of which the following is a specification.

In the accompanying drawings, Figure 1 is a plan view, Fig. 2 a central vertical section, 10 and Fig. 3 a front view, of my improved machine. Fig. 4 is a detail view of cam and head, and part of the connecting parts, whereby the bed which holds the shoe while it is being punched is oscillated.

15 Like parts are indicated by like designating letters in the several figures.

In the drawings, A represents the metal frame of the machine, which, of course, is very solid and strong. Power is applied, through 20 the pulley A' and gear A² upon the shaft A³, to the gear A⁴, loosely placed upon the shaft A⁵. From this latter shaft the punches receive their motive power.

The shoe to be punched is placed upon a 25 bed-block, B, swinging upon a pivot, B', and having a holder, B², shaped to conform to the interior of the shoe, and surrounded by openings b, corresponding in location and number with the nail-holes to be punched.

30 The shoe is applied—which is done while the bed-block is swung outward to the position shown by the dotted lines in Fig. 2—the operator sets the machine in operation through a foot-lever, C, which swings upon the pivot B', and with its inward extension raises a lever, C', so as 35 to release said lever C' from the stop C² upon the elbow-lever C³, thus leaving the vertical lever C⁴, pivoted at C⁵ upon the frame, free to swing obedient to the spring C⁶ upon the shaft A⁵. This swing or change of position by the 40 lever C⁴ shifts the moving part C⁷, to which it is connected, so that said part C⁷ clutches with the teeth upon the hub of the gear-wheel A⁴. The part C⁷ encircles the shaft A⁵, and is 45 keyed thereto by longitudinal ribs m, projecting from the periphery of the shaft.

It will thus be seen how the clutch is closed as the result of pressure by the operator upon the foot-lever. It now remains to connect the 50 remaining parts with the shaft A⁵, to which

motion is communicated by the clutch; and first I will describe the parts which oscillate the bed-block B at the proper times.

D is a cam rigidly fixed upon said shaft A⁵. It rotates in a frame, D', and to its face is secured 55 another cam, D², which comes in contact, at each revolution, with a cam-projection, D³, upon said frame D'. Said frame is adjustably held in a large surrounding frame, D⁴, to the back of which are guides d⁴, sliding in corresponding grooves in the main frame.

From the bottom of frame D⁴ depends a rigid arm, D⁵, to which are pivoted connecting-bars D⁶, and said connecting-bars are jointed to the elbow-lever C³, already mentioned. This elbow-lever is pivoted in the body of the machine at c³, and is connected, by bars D⁷, with the lower end of the bed-block B. It will thus be seen that when the cam D² comes in contact with the projection D³ and raises the 70 frame to which that projection is secured it also operates the elbow-lever, and through it and its connections draws the bottom of the bed-block inward and causes said block to assume the position shown by the dotted lines in 75 Fig. 2. This is the initial position of the bed-block at the beginning of each operative movement.

The machine is started by depressing the treadle C, and thereby lifting the lever C' off 80 the stop-pin C². This permits the spring C⁶ to move the clutch C⁷ into engagement with the driving-wheel A⁴, and the shaft A⁵ is set in motion. When the contact between said cam D² and projection D³ has ceased the frame 85 D' descends, causing the bed-block to swing to the position shown in Fig. 2 by the continuous lines, and a dwell ensues while the rounded edge of the cam D is passing the bottom of said frame. When the frame D' has descended 90 to its lowest position the lever C³ will have advanced far enough to permit the lever C' to drop behind the stop-pin C² again. During this dwell the punching is done, and the punches are retracted before the contact between the cam D² and projection D³ recommences. This contact gradually raises the 95 frame and actuates the elbow-lever, as before, thereby tilting the bed-block forward again and crowding back the lever C⁴, actuating the 100

shifting part of the clutch, and releasing the engagement between the shifting and stationary parts of the clutch. This operation, when complete, leaves the machine in its initial position ready to receive another shoe, with all the punching mechanism at rest.

At the time the frame D' is raised by the cam D² the flattened side of the cam D will be down, and thus the frame is permitted to rise. At other times the rounded edge is in contact with said frame and holds it down firmly, and thereby, through the intermediate parts, the bed-block is securely retained in position during the punching operation.

The punching devices are arranged radially at either side of the machine, so they will coincide with the openings in the bed-block. They are constructed of punch-rods E, each held in a holder, E', by a set-screw, e, said holder sliding in a groove upon the end of an upright frame, E². There is such number of these upright frames as there are holes to be punched, and they are adjustable to or from each other, as their fastenings—to wit, the front and rear bolts E³, having their heads in circular grooves E⁴ on the bed of the main frame—permit any desired change in this regard. The punch-rods pass through and are braced and guided by openings through the forward projections, E⁵, of the upright frames E², and they and their holders are forced down to their work of punching the shoe by levers E⁶, pivoted in the outer ends of the upright frames, and resting at their forward ends in a recess, e', in a head, E⁷, which is moved up and down by an eccentric, E⁸, upon the shaft A⁵, and a square box, E⁹, surrounding said eccentric, such movement being sufficient to give the requisite action to the punches. The continued rotation of the eccentric raises the head E⁷, and with it the levers E⁶. The punches follow the levers E⁶ upward by virtue of the connecting-pieces E¹⁰.

The box E⁹, surrounding the cam, is loosely held in a receptacle, E¹¹, in the head E⁷, and said head is in turn held in a recess in the main frame. The box E⁹, of course, has freedom to move laterally in its recess in obedience to the movements of the eccentric; but it at all times bears squarely at the top and bottom of said recess.

F is a stationary keeper secured to the bed of the machine, and located as shown in the drawings, its function being to hold down the toe of the shoe during the punching, which it is caused to do by overlapping that part when the bed-block is swung back into the machine. I also provide at the front two keepers designed to press down upon the heels of the shoe during the same time. These keepers F' are made in a single piece, as shown in Fig. 3, pivoted at either side of the bed-block to the main frame, as at F², and swung on such pivots by a connecting-rod, F³, extending to and attached to the bed-block. By these two devices the shoe is automatically and securely

held down upon the bed-block while it is being operated upon, and they release their hold as soon as the bed-block begins to move out from under the punches.

G is an arm secured to the main frame of the machine, extending around to the front of the bed-block, and provided with two fingers, g g, so located with reference to the bed-block that when the latter is tilted forward after each punching said fingers will catch under the heels of the shoe and loosen it from the holder or die upon the bed-block.

The construction of the punches is such that the punches proper, which are the parts most likely to need repairs, may be easily replaced. Their inclination may be changed, also, by changing the upright frames, and as each punch is independent of the others, any one may be changed or removed at pleasure, and the machine may be used with a greater or less number, as desired.

The whole operation, after the shoe is placed upon the holder and the mechanism is set in motion, is automatic.

I claim—

1. The combination, in a machine for punching horseshoes, of a series of independent nail-hole punches arranged in the holders and surrounding the shoe-support, said holders being jointed to radial arms E⁶ and operated simultaneously by a sliding head, E⁷, and an actuating-shaft, A⁵, said sliding head, and said shoe-support, substantially as specified.

2. In a machine for punching horseshoes, a series of nail-hole punches secured in independent holders arranged around the shoe-support and jointed to a series of radial arms, E⁶, and a reciprocating head, E⁷, whereby said punches are actuated simultaneously by motion derived from the main shaft, combined with a swinging bed-block and cams on the main driving-shaft, connecting-rods D⁵ D⁶ D⁷, and intermediate bell-crank, O³, whereby said bed-block is automatically moved into and out of position, substantially as set forth.

3. The combination, in a horseshoe-punching machine, of the series of punches, the movable bed-block, the shaft A⁵, the cams, the eccentric, and the clutch upon said shaft, and the intermediate parts, whereby power is conveyed from said shaft to said punches and bed-block, substantially as set forth.

4. In a machine for punching horseshoes, the combination, with the punches and the moving bed-block, of the swinging keeper F', pivoted to the frame and operated by the swinging bed-block to press down upon and hold the shoe during the punching operation, substantially as set forth.

5. The combination, in a horseshoe-punching machine, of the following instrumentalities, to wit: a series of independent punches, one for each nail-hole to be punched, mechanism for automatically operating said punches, a bed-block for supporting the shoe, moving in before and out after the operation of the

punches, mechanism for operating said bed-block, and devices for holding the shoe upon the bed-block, substantially as specified.

6. The combination, with a horseshoe-punching machine, of the punching mechanism described, consisting of inclined punch-rods, holders for said rods, sliding in the laterally-adjustable radial upright frames, the levers pivoted at one end to said frames, with their other ends held in the vertically-moving head E⁷, and said head, substantially as set forth.

7. In a horseshoe-punching machine, the

swinging bed-block B and actuating-shaft A⁵, provided with cams D D², connecting-rods D⁶ and D⁷, and intermediate bell-crank, C³, combined with a clutch C⁷, controlling-lever C⁴, and trip C' C², whereby the forward swing of said bed-block causes the disengagement of said driving-shaft from the driving-gear A⁵, as set forth. 15
